UNITED STATES PATENT OFFICE.

ROBERT E. JACK, OF OSHKOSH, WISCONSIN, ASSIGNOR OF ONE-HALF TO
HERMAN DIESTLER, OF HORTONVILLE, WISCONSIN.

CIGAR-CLIPPER AND MATCH-LIGHTER.

SPECIFICATION forming part of Letters Patent No. 700,331, dated May 20, 1902.

Application filed August 31, 1901. Serial No. 74,025. (No model.)

To all whom it may concern:

Be it known that I, ROBERT E. JACK, a citizen of the United States, residing at Oshkosh, in the county of Winnebago and State of Wisconsin, have invented new and useful Improvements in Cigar-Clippers and Match-Lighters, of which the following is a specification.

This invention relates to means for clipping the ends of cigars and furnishing lighted matches, and has for its object to provide a single complete machine for accomplishing both of the aforesaid results at a single operation and for agitating the matches after each 15 operation.

With this object in view the invention consists in the improved construction, arrangement, and combination of the parts of such machine, which will be hereinafter fully described and afterward specifically claimed.

In the accompanying drawings, which illustrate a machine embodying my invention, Figure 1 represents a view of the machine in right-hand side elevation, the side of the casing being partially broken away to expose to view the interior mechanism. Fig. 2 represents the machine in front elevation. Fig. 3 represents in perspective the greater portion of the interior mechanism in the position it 25 assumes at the completion of an operation, and Fig. 4 represents in perspective the same parts in the positions they assume before an operation.

Like numerals indicate the same parts in all of the figures of the drawings.

Referring to the drawings, 1 indicates the base, 2 the right-hand side, 3 the left-hand side, 4 the front, 5 the rear, and 6 the top of the casing of a preferably rectangular casing 40 in which the operating mechanism is contained.

7 indicates a transverse horizontal shaft journaled in the sides 2 and 3, upon which is secured a disk 8 and a cylindrical block or roller 9, the disk 8 supporting on one side a plate 10, having, preferably, three radial arms 11 12 13 at angles of one hundred and twenty degrees from each other and projecting slightly beyond the periphery of the disk, the 45 disk having on its opposite side an equal number of laterally-projecting lugs 14 15 16

in corresponding positions, but slightly in advance of the arms 11 12 13, while the roller 9 is provided with substantially semicylindrical longitudinal grooves 17 18 19, in number and position to correspond with the arms and lugs of the disk, each of said grooves being interrupted at about its mid-length by a segmental recess 20 in the roller. The disk 8 is adjustable on the shaft 7 and secured in 55 position after adjustment by a set-screw 21.

22 indicates a horizontal rock-bar pivoted to the base 1 and provided at its right-hand end with an arm 23, normally held in the path of movement of the lugs 14 15 16 by means 60 of a spring 24, and at its left-hand end with an arm 25, finished at its outer end as one jaw of a clamp, the other jaw of which is at the outer end of a spring-pressed lever 26, pivoted to arm 25, the jaws being normally 65 closed and having their ends bent outward to facilitate the entrance of a match.

At 27 is shown a plunger mounted to slide vertically in a guideway in the side 2 of the casing, provided at its upper end with a knob 75 28 and near its lower end with an inward projection or lug 29, the plunger being normally held in its uppermost position by a spring 30.

Secured by bolts or screws 31 31 to the inside of side 2 of the casing are bearings 32, in which is loosely mounted a vertical rod 33, bent at its upper end 34 into the path of movement and above the projection 29 and at its lower end 35 into a position to bring said end 80 85 into contact with one of the radial arms of plate 10, as hereinafter explained.

A knife 36 is secured to the plunger in position to cause it to move across an eye 37 in the front of the casing when the plunger is 90 moved.

38 indicates a hopper having its discharge-opening adjacent to and above the roller 9; 38^a, a follower or cover for the hopper; 39, a spring arranged to press slightly against the 95 right-hand or butt end of the match 40, delivered from the hopper, and 41 a perforated or roughened plate or sheet against which the head of the match 40 is normally kept in contact by the pressure of spring 39 against its 100 butt-end.

The parts being in position as shown in

Figs. 1 and 4, with the plunger raised and the hopper supplied with matches, the plunger is moved downward by pressure on its knob, which will cause the knife 36 to cut off the tip of a cigar 42, (shown in dotted lines in Fig. 1,) projected through eye 37. The lug 29 on the plunger by pressing radial arm 11 downward will rotate plate 10, shaft 7, disk 8, and roller 9 through about one hundred and twenty degrees, during which movement lug 14 will contact with arm 23, rotate rock-bar 22, and bring arm 25, with its clamp, inward into position in the recess 20 to receive the match 40, which has been brought around in groove 17 of the roller 9, which match has been lighted by friction with plate 41 during such movement and pressed between the jaws of the clamp. The lug 14 immediately upon the clamp of arm 25 receiving said match passes out of contact with the end of arm 23, and said arm 25 moves outwardly to its normal position, so that the match can then be removed from the clamp and used to light the clipped cigar. It will be noted that as the plunger 27 moves downwardly the rod 33 will drop by gravity until the end 34 contacts with the upper bearing 32, whereby the downward movement of said rod is arrested; but plunger 27 continues its downward course until arm 11 has moved out of the path of said lug 29. Pressure upon the plunger being released, the spring 30 will raise it, the movement lost by said rod 33 permitting the lug 29 to engage the lower edge of arm 13 and swing said arm backward out of its path of movement, causing the shaft and its connections to rotate backward a short distance before affecting said rod 33. The projection 29 in the further upward movement of the plunger will engage the upper end 34 of rod 33, raising said rod and moving its end 35 beneath radial arm 12, causing the shaft and its connections to rotate forwardly a short distance, whereby the parts are in position for another operation, the lug 29 in the second operation engaging radial arm 13. This slight backward-and-forward rotation of the shaft during the upward movement of the plunger carries the roller back and forth under the hopper, thus agitating the matches therein and insuring the deposit of one of them in the next groove of the roller ready to be delivered by the next operation.

If desired for use as a house match-safe, the cigar-clipper could be dispensed with, the casing supported on a bracket on the wall, and a lock 43 provided upon the hopper-cover to engage with the plunger by means of a bolt 44.

The utility and advantages of my invention will be apparent from the foregoing description, in which I have specifically described the construction and relation of the various parts; but I desire it to be understood that I do not limit myself to the exact forms and locations of parts, as many changes and variations might be made therein with-

out departing from the spirit and scope of my invention.

Having thus fully described my invention, 70 what I claim as new, and desire to secure by Letters Patent of the United States, is—

1. In combination a hopper to contain matches, a grooved roller to receive matches from the hopper and deliver the same, a rough 75 plate in the path of movement of the heads of the matches being delivered, and a delivery-clamp in the path of movement of the roller to receive the matches therefrom, substantially as described. 80

2. In a mechanism of the class described, the combination with a suitable support, of a roller mounted therein, means for supplying articles thereto, means on said roller for carrying a single article, means for rotating said 85 roller for delivering the article carried thereby, and automatic means for oscillating said roller after each delivery, substantially as described.

3. In a mechanism of the class described, 90 the combination with a suitable support, of a roller mounted therein, means on said roller for carrying an article, means for supplying articles to said roller, means for rotating said roller for delivering the article carried thereby, and means for receiving the article to be delivered and removing the same from said roller and carrying the same to the point of delivery, substantially as described. 95

4. In a mechanism of the class described, 100 the combination with a suitable framework, of a roller mounted therein, an article-containing hopper arranged above said roller, means on said roller for receiving a single article from said hopper, means for rotating 105 said roller, a delivering-arm pivotally mounted in said framework, and means for swinging said arm into the path of movement of said article for receiving and carrying the same to the point of delivery, substantially 110 as described.

5. In a mechanism of the class described, the combination with a suitable framework, provided with a supply-receptacle, of a roller 115 mounted in said framework and communicating with said receptacle, means on said roller for receiving an article from said receptacle, means for rotating said roller for removing the article from said receptacle, and auxiliary means for removing said article from 120 said roller and carrying the same to the point of delivery, substantially as described. 125

6. In combination a hopper for containing matches, a grooved roller for receiving them therefrom, a shaft carrying the roller, a disk 125 on the shaft, lateral lugs on the disk, means for rotating the shaft, a clamp to receive the matches carried by the roller, and means operated by the lateral lugs for bringing the clamp into operative receiving position, substantially as described. 130

7. In combination, a hopper for containing matches, a shaft, a grooved roller carried thereby to receive matches from the hopper,

a disk on the shaft, radial arms on the shaft, a vertical plunger, a lug thereon to engage the arms, a clamp to receive the matches from the roller, and means for moving the clamp into receiving position and returning it to delivery position, substantially as described.

8. In combination, a hopper for containing matches, having an open bottom, a grooved roller mounted under the hopper, means for rotating the roller forward to deliver a match, and spring-controlled means for automatically oscillating the roller after each delivery for agitating the matches in the hopper, substantially as described.

15 9. In combination, a hopper for containing matches, having an open bottom, a shaft, a grooved roller thereon under the hopper, a plunger, connections between the roller and plunger for rotating the roller forward by the depression of the plunger, and means for imparting several backward-and-forward partial rotations to said roller during the upward movement of the plunger, substantially as described.

25 10. In combination, a hopper for containing matches, having an open bottom, a shaft, a grooved roller upon the shaft under the hopper, a plate on the shaft, radial arms on said plate, a plunger, a lateral projection or lug thereon, a vertically-slidable rod having its upper end bent into the path of movement of the lateral lug and its lower end bent into the path of movement of the radial arms, the contact of the lateral lug during its downward movement with the arm of the plate serving to rotate the shaft and roller forward to deliver a match, and its contact with an arm and the upper end of the vertical rod serving to reciprocally rotate the roller during the upward movement of the plunger and lug, substantially as described.

35 11. In a mechanism of the class described, the combination with a suitable framework, of a shaft mounted therein, a roller fixed to said shaft, radial arms carried by said shaft, means for engaging one of said arms for swinging the same and the shaft for a portion of a rotation, means for engaging another of said arms for swinging the same and said shaft in an opposite direction for returning the roller to the initial position after the first operation, and means for delivering a single article at each initial operation of the roller, substantially as described.

50 12. In a mechanism of the class described, the combination with a suitable framework, of a shaft mounted therein, a delivery-roller arranged on said shaft, radial arms extending from said shaft and secured thereto, a vertically-movable rod mounted in said framework, means carried thereby for engaging one of said radial arms of said shaft, and auxiliary means for imparting a return rotation to said shaft after the operation of said vertical rod whereby the said roller will be oscillated, substantially as described.

55 13. In a mechanism of the class described,

the combination with a suitable framework, of a shaft mounted therein, a delivery-roller carried thereby, radial arms secured to said shaft, means for engaging said arms for swinging the same in one direction, means for swinging the same in another direction whereby the delivery-roller will be oscillated, a delivering-arm pivotally supported in said framework, and means for swinging said arm in position to receive an article from the said roller, substantially as described.

60 14. In a mechanism of the class described, the combination with a suitable framework, of a shaft mounted therein, a delivery-roller carried by said shaft, a disk also carried by the shaft provided with laterally-projecting lugs, a delivering-arm pivotally supported in said framework and having one end thereof extending into the path of movement of said lugs, and means for rotating said shaft for delivering an article to said delivering-arm, substantially as described.

65 15. In a mechanism of the class described, the combination with a suitable framework, of a shaft mounted therein, means carried by said shaft for separating an article from a series of similar articles, a delivering-arm pivotally mounted in said framework, and means carried by said shaft for swinging said delivering-arm into position for receiving the article separated, substantially as described.

70 16. In a mechanism of the class described, the combination with a suitable framework, of a shaft supported therein, article-delivering means carried by said shaft and designed to be operated by the rotation thereof, radial arms extending from said shaft, a vertically-movable rod mounted in said framework and provided with means designed to engage one of said arms at each downward movement of said rod, whereby said shaft is designed to be forwardly rotated, the construction being such that downward movement of said rod will move the next succeeding radial arm into the path of the movement of said engaging means, whereby the said next succeeding arm is designed to be engaged and swung in an opposite direction with the upward movement of said rod to that of its former movement with the downward movement of said rod, and auxiliary means for engaging another of said radial arms for swinging the same in the direction of its initial movement after the second movement thereof, substantially as described.

75 17. In a mechanism of the class described, the combination with a suitable framework, of a shaft mounted therein and carrying article-delivering means, radial arms secured to said shaft, a vertically-movable rod arranged in said framework, a lug projecting laterally from said rod designed to contact with one of said radial arms with the downward movement of said rod for swinging said arm forwardly and bringing the next succeeding radial arm into the vertical plane of said lug whereby a return movement of

the lug is designed to strike the next succeeding arm and swing the same in an opposite direction to the forward movement, and auxiliary means for again swinging the shaft in the direction of its forward movement during the return of said vertical rod to its normal position, substantially as described.

18. In a mechanism of the class described, the combination with a suitable framework, of a shaft mounted thereon, radial arms fixed to said shaft, a vertically-movable rod arranged in said framework, a lug extending laterally from said rod, adapted to contact with one of said radial arms, a bent rod slidably supported in said framework and hav-

ing one end extending in the vertical plane of and above said lug, and the other end normally extending into the path of movement of said radial arms, said bent rod being free to move downwardly by its own weight with the downward movement of the lug, and means limiting the movement of said bent rod, substantially as described.

In testimony whereof I have hereunto set my hand in the presence of two subscribing witnesses.

ROBERT E. JACK.
